UNITED STATES PATENT OFFICE.

SVEN AUGUST ESKILSON, OF STOCKHOLM, SWEDEN.

APPARATUS FOR FLINGING OFF SUPERFLUOUS COATING WHEN TINNING, PAINTING, OR THE LIKE.

1,327,273.

Specification of Letters Patent.

Patented Jan. 6, 1920.

Application filed December 12, 1917. Serial No. 206,760.

To all whom it may concern:

Be it known that I, SVEN AUGUST ESKILSON, a subject of the King of Sweden, residing at Stockholm, in the Kingdom of Sweden, have invented a new and useful Improvement in Apparatus for Flinging Off Superfluous Coating When Tinning, Painting, or the like, of which the following is a specification.

10 The present invention relates to an apparatus for flinging off superfluous coating when tinning, painting or the like, in order to save tin or paint and also to procure an even coating.

15 Apparatus for this purpose have previously been constructed which consist of a stationary frame supporting a rotary shaft for a cage serving for receiving the objects to be treated. There are also apparatus in 20 which the frame is rotatable on a stationary shaft.

The purpose of the present invention is to provide an apparatus of the kind referred to, which shall be convenient to handle and 25 by means of which a work-piece may easily be picked up at one place, transferred for instance to a tin bath or the like, thence to a water trough, and finally to a fourth place where the ready work-pieces are collected, 30 without having to follow an appointed path.

The invention is principally characterized by a rotatable gripping device for the objects to be tinned, painted, etc., said gripping device being removable or portable 35 either separately, or together with the apparatus. The said gripping device is preferably provided with a coupling gear for connecting the same to a rotating member or to a member which may be caused to rotate 40 when the connection has been effected. The member to which the gripping device may be connected and which may be rotated when the connection has been effected, may consist of a movably journaled shaft provided with a 45 coupling gear by means of which it may be connected with a rotating shaft. According to another embodiment of the invention the rotating member, the coupling gear and the gripping device are provided within a 50 common removable or portable casing, for instance in such manner that a shaft is rotatably journaled within a portable casing, the said shaft being connected with a motion-transmitting flexible shaft or the like 55 as well as with another shaft carrying the

gripping device, a coupling gear being arranged between the shafts for connecting the same with one another. According to a further embodiment of the invention a shaft is rotatably journaled in a removable or portable casing which shaft supports a friction wheel, disk or the like by means of which the apparatus may be brought into operative engagement with rotating friction rolls, 60 disks or the like, and the gripping device for the objects to be tinned or the like. The apparatus may also consist of an electric motor arranged within a portable casing, the gripping device being connected to the shaft of the motor which latter is connected with a 65 source of current by means of a flexible conductor.

With this apparatus it is possible to grip a work-piece, submerge it in the tin bath and raise it with the apparatus and immediately 70 to put the work-piece into rotation above the level of the bath, whereby it is attained that the tin flung off drops into the bath, and also, on account of the work-piece being prevented from cooling by it being held in the 75 warm air above the bath, that the surface of the treated object becomes more even and that more tin is flung off than when, as heretofore practised, the work-piece upon removal from the bath is transported to 80 and fixed in a centrifugal apparatus in order to have the tin flung off. It is also apparent that with the present apparatus the 85 tinning will be effected more rapidly, because when the tin has been flung off, the 90 work-piece may be directly submerged into water for cooling the same, and may be removed from the apparatus immediately afterward.

In the accompanying drawings a few embodiments of the invention are shown by way of example: Figure 1 represents one embodiment in elevation. Fig. 2 shows a longitudinal vertical section of a second embodiment of the invention, and Fig. 3 shows 100 the same embodiment viewed from above. Fig. 4 is a vertical section of a third embodiment, and Fig. 5 shows diagrammatically and to a smaller scale a detail thereof. Fig. 6 is a vertical section through a fourth 105 embodiment, and Fig. 7 shows to a smaller scale an elevation of a fifth embodiment. Fig. 8 illustrates a sixth embodiment of the invention.

In the embodiment shown in Fig. 1, 1 is 110

- the gripping device for the objects to be tinned, which gripping device is provided with an eye at the top by means of which it may be attached to a hook 2 on the lower end 5 of a shaft 3, which is journaled in a bushing 4 to the upper end of which a friction disk 5 is secured. The bushing 3 is movably attached by means of a lever 6 and preferably also through a link 7, to a frame 8, in which 10 a rotary friction disk 9 is journaled. The object having been dipped into the tin bath by means of the gripping device 1, and the latter having been hung on to the hook 2, the disk 5 is moved up against the disk 9 by 15 means of the lever 6, whereby the gripping device and the object are caused to rotate so that the tin is flung off. When a sufficient amount of tin has been flung off the lever 6 is lowered, so that the friction disk 5 comes 20 into engagement with a brake lug 10 on the frame 8 and is thus caused to stop. The frame 8 is preferably located so that during the rotation the gripping device 1 together with the object will be situated right above 25 and near the level of the tin bath. In the embodiment of the gripping device shown, the object is fixed and retained in the same by its own spring action.

- In the embodiment shown in Figs. 2 and 30 3, the shaft 12 is journaled in the casing 11, said shaft 12 being connected with a flexible motion-transmitting shaft 13. The shaft 12 is provided with suitable thrust-bearings 14 and 15. A second shaft 16 is journaled in 35 alinement with the shaft 12 in a bushing 17 in the lower portion of the casing 11, and runs by means of a thrust-bearing 18 in a slide-block 19 which is movable up and down in the casing 11 by means of a tiller 20 secured to the same, which tiller may be operated by a finger when grasping the handle 21. The shaft 12 is provided with a conical recess 22 at its lower end, and the shaft 16 has a corresponding conical pivot 23 at its 40 upper end, hence the said shafts may be coupled with each other, when the tiller 20 and the slide-block 19 are moved upward. The shaft 16 then rotates with the shaft 12, as long as the tiller 20 is kept raised. When 45 releasing the tiller 20, the slide-block 19 will be pushed downward by the spring 24 which is inserted between the block and the casing or a part thereof. The flange 25 of the shaft 16 is then pushed against the ring 26 in the slide-block 19 and the collar 27 on the shaft 16 is brought into engagement with the plate 28 fixed to the casing, thus braking the shaft 16. At the lower end of the shaft 16 a fork 29 or other holding device is arranged on to 50 which the objects to be tinned or painted are pressed and are secured through the spring action of the fork.

The tinning of an object, for instance of a liner plate of a separator for which the fork 29 illustrated in the drawing is par-

ticularly adapted, is performed in such manner, that the liner plate is pressed on to the fork, whereupon it is submerged in the tin bath and then raised to a position just above the level of the bath. The tiller 20 is now 70 raised, so that the shafts 12 and 16 are brought into engagement with one another, whereby the liner plate is put into rotation. Superfluous tin having been flung off, the same falling into the tin bath, the liner plate 75 is dipped into water in order to be cooled, whereupon it is removed, and a new liner plate is gripped for treatment. The course takes but a very short time, and in the manner described the tinning becomes very even 80 and uniform and very little tin is required, besides which practically all superfluous tin may be saved as the flinging off is performed above the bath.

It is evident that in the embodiment shown 85 many modifications may be made. For instance, the transmission of motion may be effected by means of a telescopically arranged shaft with universal joints, or the coupling gear may be of a different kind, and so forth. 90 The gripping device may also be of different construction according to the various objects to be held by the same. The coupling gear may be located at some other point between the motor from which the motion is transmitted and the gripping device. In the embodiment shown the upper shaft may be 95 slidable longitudinally and the lower shaft not slidable or both shafts may be prevented from moving in axial direction, a suitable 100 movable coupling and braking device being provided between the shafts.

In the embodiment according to Fig. 4 the work-piece to be tinned, etc., is attached in any suitable manner to a fork or a holder 31. 105 This fork or holder is connected with one end of a rotating member, for instance a shaft 32. The shaft 32 is journaled in a bushing 33, ball-bearings 34 being preferably arranged between the shaft and the 110 bushing. A handle 35 is pivotally connected with the bushing 33 by means of arms 36 which turn on shoulder screws 37 secured to the bushing 33. A spring 38 is provided in the handle which spring tends to push the 115 handle away from the bushing. A friction disk is secured to the other end of the shaft 32 which friction disk may consist of leather disks 40 clamped between two plates 39. The ends of a brake band 41 are secured to 120 the handle 35, the brake band being laid around the shaft 32 and bearing directly against the shaft or against a member secured to the same, for instance a brake disk 42. By the action of the spring 38 the brake 125 band is brought into engagement with the brake disk.

When using the apparatus the same is supported by means of the handle 35, and the work-piece attached to the fork or holder 130

31 is dipped into the tin bath. The apparatus is then raised and the friction disk 40 brought to bear against two rotating friction rolls 43 (Fig. 5), these latter being arranged 5 at a suitable height above the bath. Owing to the pressure against the rolls 43 the handle is moved toward the bushing 33 while the spring 38 is being compressed, and the brake band 41 thus releases the brake disk 42, so that the shaft 32 is free to be driven 10 by the rolls 43 at a rate of speed which is sufficient to cause the superfluous tin to be flung off from the work-piece on account of the centrifugal force. When the apparatus 15 is withdrawn from the rolls 43 the spring 38 moves the handle 35 and the bushing 33 with the shaft 32 in opposite directions so that the brake band 41 is brought into engagement with the brake disk 42 and brakes 20 the shaft.

In the embodiment according to Fig. 6 the handle 75 is rigidly connected with the bushing 73 in which the shaft 72 is journaled and in which in this case it is also movable longitudinally. The shaft 72 is provided with a 25 braking device secured to the same, for instance a flange or brake disk 44. A spring 45 is arranged in the bushing 73 said spring operating through a cup 46 and balls 47 to 30 force the brake disk 44 to bear against a member connected with the bushing 73, for instance a nut 48 screw threadedly attached to the bushing. The shaft 72 is provided at the end opposite the fork or holder 71, 35 with a ball 49 or some other equivalent member, and the rotary member 50 from which the motion is to be transmitted to the shaft 72, is provided with a recess 51 which may, for instance, have the conical form 40 shown in the drawing so as to be capable of receiving the ball 49.

When the shaft 72 together with the fork 45 71 and the work-piece held by the same are raised from the bath by means of the handle 75 the ball 49 is introduced into the recess 51 in the rotary member 50, whereby the shaft 72 is caused to rotate. At the same time the shaft is moved longitudinally in the bushing 73, the spring 45 being then 50 compressed and the brake disk 44 removed from the nut 48, thus allowing the shaft to rotate freely. When the ball 49 is later disengaged from the recess 51 by means of the handle 75, the spring 45 again moves the 55 brake disk 44 toward the nut 48, thus braking the shaft.

As will be understood from the modified arrangement illustrated in Fig. 7, the shaft 82 supporting at one end the gripping device 81 and rotating in the casing 83 supported 60 by means of the handle 85, may be provided with a friction disk 52 which, when the shaft is to be rotated, is brought into engagement with a friction disk 53 rotating around a 65 horizontal axis.

The transmission of motion to the shaft from the member or members driving the same may for instance also be effected by means of toothed gearing or by a belt, chain, rope or the like running over pulleys, or a 70 reciprocating pawl may be used, the shaft then being provided with a corresponding transmission gear as for instance a belt or a rope pulley, a friction wheel, toothed wheel, chain wheel and so on. The shaft might 75 also be provided with a wing-wheel or the like which is subjected to a current of air, water or other fluid for producing the motion. Other modifications could of course 80 also be made. The braking device for instance need not be automatic in its action, but may be influenced by hand through a tiller or the like operated from the handle.

I claim:

1. In an apparatus of the class described, 85 a driving element, a portable driven element, means for transmitting motion from said driving element to said driven element, and a gripping device carried by said driven element and adapted to rotate therewith, said 90 gripping device being designed to hold the article to be coated, and said driven element being movable so as to render said transmitting means operative or inoperative as desired, whereby said article after the same 95 has been coated may be revolved to remove surplus coating therefrom by centrifugal force.

2. In an apparatus of the class described, 100 a driving shaft, a portable driven shaft, gripping jaws for holding the article to be coated carried at one end of said portable shaft, and means for moving said portable shaft to effect a driving connection with said driving shaft, whereby said jaws are 105 revolved thereby removing surplus coating from said article by centrifugal force.

3. In an apparatus of the class described, a driving shaft, a portable driven shaft, gripping jaws for holding the article to be 110 coated carried at one end of said portable shaft, means for moving said portable shaft to effect a driving connection with said driving shaft, whereby said jaws are revolved thereby removing surplus coating from said 115 article by centrifugal force, and brake mechanism for stopping the rotation of said portable shaft upon a disengagement of said driving connection.

4. In an apparatus of the class described, 120 the combination with a fixed driving shaft, of a portable driven shaft, gripping jaws carried at one end of said portable shaft and designed to hold the article to be coated, and means for operatively connecting said portable shaft to said driving shaft after said article has been coated, whereby said article 125 may be revolved to remove the surplus coating therefrom by centrifugal action.

5. In an apparatus of the class described, 130

a fixed driving element, and a portable carrier having a plurality of jaws, and means for transmitting a rotary motion thereto from said driving element.

5 6. In an apparatus of the class described, a portable carrier having a plurality of jaws for gripping the article to be coated, a driving element, and means for transmitting rotary motion from said element to said jaws

10 to thereby remove surplus coating from said article by centrifugal force.

7. In an apparatus of the class described, a fixed driving element, a bushing, a rotatable shaft journaled therein having a plu-

15 rality of jaws depending from one end thereof designed to grip the article to be coated, means on the other end of said shaft adapted to transmit motion thereto from said driving element, and means for moving

20 said bushing in such wise as to bring said first-named means into engagement with said element.

8. In an apparatus of the class described, a driving element, a portable carrier com-

25 prising a rotatable shaft, and a plurality of jaws depending from one end of said shaft and designed to grip the article to be coated, the other end of said shaft being adapted for detachable engagement with said driv-

30 ing element, whereby motion therefrom may be transmitted to said shaft, and means for effecting and maintaining such engagement.

9. In an apparatus of the class described, a driving element, a portable carrier com-

35 prising a rotatable shaft, a plurality of jaws depending from one end of said shaft and designed to grip the article to be coated, the

other end of said shaft being adapted for detachable engagement with said driving element, whereby motion therefrom may be 40 transmitted to said shaft, means for effecting and maintaining such engagement, and brake mechanism for arresting the motion of said shaft immediately upon the removal of the same out of engagement with said 45 element.

10. In an apparatus for flinging off superfluous coating when tinning, painting or the like, the combination of a stationary frame, a driving member in said frame, a casing 50 capable of being moved in all directions, a shaft journaled in said casing, a gripping device secured to said shaft, means on said shaft adapted to engage said driving member, a brake disk on said shaft, a handle piv- 55 oted to said casing, a brake band surrounding said brake disk and secured to said handle, and a spring inserted between said casing and said handle and tending to move said handle relatively to said casing so as to 60 cause said brake band to engage said brake disk.

11. In an apparatus of the class described, a driving element, a portable carrier com-

65 prising an elongated bushing, a rotatable shaft journaled therein having a plurality of jaws depending from one end designed to grip the article to be coated, and means at the other end of said shaft adapted to trans-

70 mit motion thereto from said driving ele- ment when said carrier is moved in such wise as to bring said means into engage- ment with said element.

SVEN AUGUST ESKILSON.
